ABSTRACT: Phase-focusing means are introduced into a traveling wave electron interaction device to optimize exchange of electron kinetic energy with electromagnetic waves propagated along an adjacent wave-guiding structure by providing an intermediate phase velocity profile at a relatively low level of electron beam energy extraction and well before tube saturation. The resultant redistribution of the guided wave phase velocity provides a delay in the electromagnetic circuit sufficient to permit advancement and desynchronizing of electron bunches to a position in the decelerating field of the propagated waves where the forces on the electrons are substantially minimal. Retention of electrons for longer periods in the decelerating field region of the circuit waves has resulted in a highly significant enhancement in efficiency in traveling wave tube performance. Application of similar phase velocity shift techniques has substantially reduced harmonic frequency power content leading to premature tube saturation in high-gain octave bandwidth devices to yield improvements in efficiency by approximately a factor of 2.

**TRAVELING WAVE ELECTRON INTERACTION DEVICE
HAVING EFFICIENCY ENHANCEMENT MEANS**

BACKGROUND OF THE INVENTION

1. Field of the Invention

The invention relates to traveling wave electron interaction devices for amplification or generation of high-frequency electromagnetic wave signal energy.

2. Description of the Prior Art 0.63

Traveling wave devices commonly incorporate a wave-guiding structure of a predetermined periodicity such as, for example, a helix for propagating high-frequency (RF) electromagnetic energy to be amplified by extracting kinetic energy from a high-power beam of electrons. The wave energy travels along the structure at a velocity less than the velocity of light. The electric and magnetic fields of such energy induce perturbations in the beam in the form of electron packets or bunches having a fundamental frequency component at substantially the frequency of the energy on the wave-guiding structure. Numerous harmonic frequency components may also be present in the perturbed electron beam. Conventionally, in such devices the electron beam is translated along the length of the guiding structure which retards the velocity of electromagnetic circuit waves until a synchronous relationship is established to optimize exchange of energy between the beam and waves.

Electron bunches which traverse the interaction path at a group velocity considered to be "in step" with the retarded electromagnetic fields then move at substantially the phase velocity of the wave-guiding structure. The electron beam, therefore, becomes simultaneously velocity and density modulated along its path of travel until a saturation point is reached where the kinetic energy extracting is maximum and the beam packets become disarranged. The electron beam modulation is a result of the phenomenon known in the art as "phase focusing" and intensifies progressively along the beam path towards the output end of the device where a collector electrode is positioned.

The high-frequency RF energy devices under consideration, therefore, provide for the continuous and prolonged interaction between electrons and electromagnetic fields on the guiding structure. Such devices are generically referred to in the art as traveling wave electron interaction tubes and may be characterized as of the "backward or forward wave type." In a backward wave device the electron beam travels at a velocity which is synchronous with the phase velocity of a traveling wave space harmonic component moving in a direction opposite to that of the energy flowing along the wave-guiding structure. The electron beam, therefore, travels in one direction and the energy of the induced wave travels in the opposite direction. In forward wave devices the electron beam and energy of the induced wave characteristically travel in the same direction. The wave-guiding structure in the backward-wave-type device is constructed so that the phase velocity of the fundamental frequency-determining component travels in a direction inverse to the direction of the electron group velocity. In contradistinction, a forward wave device is provided with a wave-guiding structure so constructed that the phase velocity of the fundamental frequency component is in the same direction as the electron group velocity. The expression "fundamental" utilized in the description of the invention is defined as that component of an electromagnetic wave having the largest phase velocity.

The high-frequency electric fields of the propagated waves have transverse and axial components. The axial component accelerates and decelerates the velocity of the electrons and brings them into a favorable phase focused position to thereby give up their energy to the electric field of the wave and enhance its amplitude. To an electron moving in a reference plane with the same velocity as the phase velocity of the wave the high-frequency axial field appears stationary. The axial component of the field, therefore, is primarily involved in the induced beam modulation. It has been noted in the art that

with more electrons in the decelerating or retarding field of the high-frequency electric fields of the propagated waves a net increase in transfer of energy occurs. In traveling wave tubes a significant performance parameter to be considered is

5 "efficiency" which is a measure of the energy converted from kinetic energy on the beam to the RF energy in the wave traveling adjacent to the beam. This parameter is an arithmetic ratio of the RF energy output power to the input power and generally values of 20 percent and under have had to be accepted. In existing systems with rather high voltage supplies already required for biasing the wave-guiding structure relative to the electron beam source any increase in efficiency must desirably be made utilizing present tube structures and existing power supplies.

10 Several methods have been heretofore advanced in the art to increase tube efficiency characteristics. Observers have, however, suggested the application of such enhancement techniques only in the region of the beam path where the electron bunches slow down and electrons slip into the accelerated region. These faster moving electrons are considered to be out of phase and actually extract energy from the high-frequency waves on the wave-guiding structure. One prior art technique involves reducing the phase velocity of the

15 waves by changing the pitch of the guiding structure components in the appropriate manner to vary the phase velocity. Such devices, therefore, would require the pitch of, for example, a helix-type structure to be altered to slow the phase velocity down progressively near the output end of the device.

20 U.S. Pat. No. 2,846,612, issued Aug. 5, 1958 to T. E. Everhart exemplifies this technique. Still another technique involves the application of separate voltage potential jumps to the guiding structure particularly at intermittent points where the electrons in the beam have slowed down. The technique requires the addition of numerous voltage supplies at increased expense together with accompanying disadvantages. An illustration of the voltage jump technique may be found in U.S. Pat. No. 2,817,037, issued Dec. 17, 1957 to R. W. Peter.

25 30 35 The foregoing techniques while improving efficiency performance in traveling wave electron interaction devices, do not prepare or "precondition" the beam modulation at low levels of energy extraction for the purpose of optimum efficiency enhancement. Further, in such devices utilized for octave bandwidth applications the presence of interfering harmonic frequency power at the low or fundamental frequency end of the band has led to very low efficiency in performance due to premature tube saturation.

40 45 An application for the employment of the devices under consideration would be phased array radar systems wherein the antenna remains stationary while the radar beam is transmitted in a scan pattern electronically at very fast rates of speed. Traveling wave tube amplifier chains feed a plurality of the antenna elements to radiate many millions of watts of energy over a scanning wave front. Rather large on-site voltage sources are required when one considers, for example, that to achieve an output RF signal of 1 watt approximately 20 watts of beam power is required in tubes having only a 20-percent efficiency. Enhancement of efficiency, therefore, will provide for higher power output radar signals to increase scanning distances without altering overall tube dimensions or on-site power facilities. In some instances tube sizes may even be reduced as a result of the 50-60-percent efficiencies envisaged in the practice of the present invention at specific frequency ranges.

SUMMARY OF THE INVENTION

50 55 60 65 70 75 In accordance with the present invention a unique result has been achieved in increasing efficiency in traveling wave devices by preconditioning electron beam modulation through novel phase-focusing means. The phase velocity of propagated waves on the electromagnetic wave-guiding circuit adjacent to the beam may be altered in such a manner as to deliberately shift the phase of the modulated electron bunches and in-

introduce a desynchronization effect at low levels of beam modulation. The criteria to be considered involves shifting of the electron bunches further forward in the decelerating field of the sinusoidal electromagnetic electric fields thereby providing for longer periods of extraction of beam energy before tube saturation. The overall profiling of the phase velocity characteristics of the electromagnetic waves to produce a desired result is based on a computerized output of a mathematically simulated model having programmed inputs of electron and tube structural characteristics. The computer program is based on a normalized nonlinear large signal analysis disclosed in the art by such authorities as J. E. Rowe, P. K. Tien, H. C. Poulter, M. E. El-Shandwily and A. J. Giarola in references to be hereinafter renumbered. An intermediate velocity is produced by a circuit phase shift at substantially low levels of beam modulation where the interaction between electrons and waves is substantially minimal and power levels are in the order of, for example, 1-1 percent of the DC beam power. The motion induced in the modulated beam bunches primarily advances the beam velocity relative to the wave toward the forward portion of the decelerating field.

The practice of the invention is not restricted to any particular wave-guiding circuit structure and efficiency enhancement will be realized in devices employing helices, as well as interdigital delay lines, ring and bar lines and any other periodically loaded structures. The position of the beam conditioning to shift electron velocity in a predetermined manner is accurately located relative to the predicted bunching phenomena for any particular tube construction. The wave-guiding structure also can be varied in many different ways selected by the tube engineer. Such modification techniques may comprise severs, negative and positive tapers, closer-spaced periodic structures, voltage jump, lumped phase shifters or any other well-known methods, either individually or in combination. The important characteristic to bear in mind is that the intermediate velocity to introduce the element of desynchronization occurs at low levels of beam modulation and energy extraction considerably before tube saturation. The duration desired for the desynchronization effect before restoration of the synchronous beam and wave relationship is also subject to analysis in accordance with the programmed output of the computer study.

In an exemplary embodiment of a traveling wave device for high-gain relatively broadband high-frequency applications the efficiency factor was increased from 20 to 41 percent. An octave bandwidth embodiment has also evolved with virtually harmonic free performance and efficiency doubled from 15 to 30 percent. Tube efficiencies of 50 to 60 percent and reduced size will now be realizable through the utilization of the invention as well as depressed collector operation, which permits even further efficiency gains. Further, the additional measure of stability afforded by the velocity shift technique reduces backward wave oscillations.

BRIEF DESCRIPTION OF THE DRAWINGS

The invention, as well as the details for the provision of preferred embodiments will be readily understood after consideration of the following detailed description and reference to the accompanying drawing wherein:

FIG. 1 is a schematic representation of a prior art traveling wave device of the forward wave-helix type;

FIG. 2 is a plot of the programmed response of phase and velocity of an electron beam in a simulated device without velocity shift profiling;

FIG. 3 is a plot of the programmed response of phase and velocity of an electron beam in a simulated device having a wave phase velocity shift;

FIG. 4 is a schematic representation of a method of implementing the invention in a helix-type traveling wave device;

FIG. 5 is a diagram of the profile of the wave phase velocity ratio along the axial length of the device;

FIG. 6 is a diagrammatic representation of an alternative embodiment of the invention incorporating tapers, as well as a velocity shift in the propagated wave profile;

FIG. 7 is a perspective view of a ring and bar delay line structure embodying the wave phase velocity profile shown in FIG. 6;

FIG. 8 is a graph of the normalized force versus phase for fundamental and harmonic waves near tube saturation;

FIG. 9 is a graph of the relative phase of beam charge density versus number of beam wavelengths;

FIG. 10 is a graph of the power conversion efficiency relative to the force field along the tube length of illustrative devices with and without the velocity shift;

FIG. 11 is a graph illustrating power gain as a function of distance in beam wavelengths for devices with and without the velocity shift;

and FIG. 12 is a schematic representation of a device having a separate coupled phase shifter.

DESCRIPTION OF THE PREFERRED EMBODIMENT

Referring now to the drawings, FIG. 1, particularly a wave-guiding structure 2 is illustrated extending axially within an envelope 4. The wave-guiding structure has been illustrated as a unifilar helix having an equal number of spaced turns, however, as previously noted any other guiding structure may be employed. Microwave energy to be amplified is coupled to one of the respective ends of the helix by input means 6 and output coupling means 8 disposed at the opposing end of the device. An electron beam emitter source 10 is disposed at the end of the tube envelope adjacent the input means 6 and includes means for guiding the stream of electrons 12 axially through the helix 2. Adjacent the output end of the envelope a collector electrode 14 is shown to provide for collection of the spent electron beam.

The electron emitter 10 comprises an emissive cathode 16 and heater coil 18 together with suitable leads extending through the envelope for connection to appropriate DC voltage biasing sources. A beam-focusing member 20 is provided in the intermediate region between the input end of the helix and the cathode emitter. This member is biased positively a sufficient voltage to accelerate the electrons along the desired trajectory path. A grid control electrode 22 is positioned adjacent to the cathode emitter and is biased by a DC variable supply 24. Magnetic-field-producing means 26 surround the overall tube envelope to assist in providing a longitudinal magnetic field parallel to the path of the electron stream. The illustrated device is referred to in the art as of the "O" and forward wave type for amplification of electromagnetic energy.

Before proceeding to a detailed disclosure of embodiments of the invention the large signal analysis using digital computer techniques to determine simulator tube characteristics will be examined. The nonlinear multisignal large signal analysis has been employed to study both fundamental and harmonic frequency generation as it is related to traveling wave devices having relatively nondispersive wave-guiding structures. As is well known in the art the term "dispersive" refers to the ratio of phase velocity of the traveling waves and the group velocity of the traveling wave and a nondispersive structure would be one in which the ratio is substantially equal to unity over the frequency range utilized.

Basically, the programmed mathematical model is a direct specialization of the large signal analysis of J. E. Rowe, Transactions, Professional Group of Electron Devices IRE, Vol. ED3, pp. 39-57, Jan. 1956 and is a straightforward extension of the one-dimensional analysis of H. C. Poulter, Technical Report No. 73, ONR Contract NGonr 251(07), Electronics Research Laboratory, Stanford University, Jan. 1954, as well as P. K. Tien, Bell System Technical Journal, Vol. 35, pp. 349-374, March 1956.

The employed analysis is based on the following assumptions:

1. The interaction between the RF electromagnetic wave and the electron beam occurs in only one space harmonic component of the total circuit field at each frequency.
2. The RF electric field is uniform across the beam, which is constrained to have no radial velocity component.
3. The phase velocities of the beam and circuit wave are much less than light. Therefore, nonrelativistic mechanics can be employed and Poisson's equation can be used in place of the wave equation for the determination of the space charge fields.
4. RF magnetic fields can be neglected.

Using a continuous transmission line to represent the traveling wave circuit for the desired space harmonic, it has been shown by the aforereferenced Poulter, Rowe, as well as M. E. El-Shandwily, University of Michigan Technical Report No. 85, Electron Physics Laboratory, Ann Arbor, Mich., June 1965, that circuit voltage can be related to the beam charge density at the nth angular frequency (ω_n) by:

$$\frac{\partial^2 V_n}{\partial t^2} - v_n^2 \frac{\partial^2 V_n}{\partial y^2} + 2\omega_n C_n d_n Z_n v_n \frac{\partial V_n}{\partial t} = v_n Z_n \frac{\partial^2 p_n}{\partial t^2} + 2\omega_n C_n d_n v_n Z_n \frac{\partial p_n}{\partial t} \quad (1)$$

Where C_n and d_n are the well-known J. R. Pierce gain and loss parameters respectively denoted in his text "Traveling Wave Tubes", D. VanNostrand Co., New York 1950. The beam coupling impedance Z_n is that for the appropriate unloaded circuit wave space harmonic having a phase velocity v_n .

According to custom, we define two normalizations distance and wave voltage amplitude. The normalized distance is given by:

$$y = \frac{C_1 \omega_1 z}{u_0} \quad (2)$$

where u_0 is unloaded beam velocity and z is the axial position along the circuit. The circuit wave voltage amplitude is normalized by:

$$V_n = \frac{Z_1 I_o}{C_1} A_n(y) e^{-i\phi_n} \quad (3)$$

where I_o = DC beam current.

In these normalizations, the phase of the nth harmonic is related to the individual charge group phase by the equation:

$$\Phi_n(z, t) = \omega_n(z/u_0 t) - \theta_n(z). \quad (4)$$

where $\theta_n(z)$ is the phase lag of the circuit wave at z relative to a moving reference frame having the initial beam velocity, u_0 .

Application of the continuity equation and a Fourier expansion of the beam charge density together with the previously stated relations result in the desired large-signal circuit equations which now follow:

$$\frac{\partial^2 \theta_n}{\partial y^2} = -\frac{1}{A_n} \left\{ 2 \frac{dA_n}{dy} \left[\frac{d\theta_n}{dy} \frac{n}{C_1} \right] + \frac{n^2}{\pi C_1} (1 + C_n b_n) \frac{Z_1}{Z_2} \left[\int_0^{2\pi} \frac{\sin \phi_n}{1 + 2C_1 u} d\phi_0 \right] - 2C_n d_n \left[\int_0^{2\pi} \frac{\cos \phi_n}{1 + 2C_1 u} d\phi_0 \right] \right\} + 2n^2 C_n d_n \left\{ \frac{1 + C_n b_n}{C_1} \right\}^2 \quad (5a)$$

$$\frac{d^2 A_n}{dy^2} = A_n \left\{ \left[\frac{d\theta_n}{dy} \frac{n}{C_1} \right]^2 - n^2 \left[\frac{1 + C_n b_n}{C_1} \right]^2 \right\} - \frac{n^2}{\pi C_1} (1 + C_n b_n) \frac{Z_1}{Z_2} \left\{ \int_0^{2\pi} \frac{\cos \phi_n}{1 + 2C_1 u} d\phi_0 + 2C_n d_n \left[\int_0^{2\pi} \frac{\sin \phi_n}{1 + 2C_1 u} d\phi_0 \right] \right\} \quad (5b)$$

where b_n is the Pierce velocity parameter.

Since a ballistic approach is employed, we can introduce the normalized charge group velocity:

$$\frac{dz}{dt} = u_0 [1 + 2C_1 u(z, t)]. \quad (6)$$

The appropriate phase equation can then be written as:

$$\frac{\partial \phi_n}{\partial y} + \frac{d\theta_n}{dy} = \frac{2nu}{1 + 2C_1 u}. \quad (7)$$

Finally, the force relation can be expressed as:

$$(1 + 2C_1 u) \frac{\partial u}{\partial y} = \sum_{n=1}^N \left\{ C_1 \left[\frac{dA_n}{dy} \cos \phi_n + A_n \left(\frac{d\theta_n}{dy} - \frac{n}{C_1} \right) \sin \phi_n \right] \right\} + \frac{(\omega_p/\omega C_1)^2}{(1 + C_1 b_1)} \int_0^{2\pi} \frac{F(\phi_1 - \phi_1')}{1 + 2C_1 u} d\phi_0. \quad (8)$$

20

In this equation $F(\Phi - \Phi_1')$ is the space charge weighting function as defined by Poulter.

Equations 5, 7 and 8, therefore, comprise a complete set of differential-integral relations which can be solved in finite difference form on a high-speed digital computer.

To derive the simulated analysis of the traveling wave tube efficiencies, the frequency characteristic of both the phase velocity and the axial-beam-coupling impedance of the fundamental space harmonic associated with the wave-guiding structure are of primary consideration. Usually, during the computer operation the trajectories of 32 electron charge groups, which are initially equally spaced over one period in the time-phase domain, are followed incrementally along the length of the simulated tube. The input power of each space harmonic is related to the starting normalized circuit wave amplitude by the expression:

$$A_n(o) = \sqrt{P_n / 2I_o V_o C_1} \quad (9)$$

40 For octave bandwidth tube simulation, second harmonic power is introduced at arbitrarily small levels, such as less than 50 db. down relative to the fundamental input signal. Since no initial RF interaction is assumed to exist between signal and beam at the tube input, we can assign zero values $n/second derivatives$:

$$\text{thus, } \frac{d^2 \theta_n}{dy^2} = 0 \text{ and } \frac{d^2 A_n}{dy^2} = 0$$

Consequently, circuit equations (5a) and (5b) become:

$$\frac{d\theta_n}{dy} = \frac{n C_n b_n}{C_1}$$

and

$$\frac{dA_n}{dy} = -\frac{n A_n(o) C_n d_n (1 + C_n b_n)}{C_1}$$

55 More generally, the power along the wave-guiding circuit may be expressed by:

$$P_n = \frac{2I_o V_o C_1^2}{n(1 + C_n b_n)} \left[\frac{n}{C_1} - \frac{d\theta_n}{dy} \right] A_n^2 \quad (10)$$

and the basic electronic conversion efficiency at the fundamental frequency is calculated from the following equation:

$$EF = 200 C_1 A_1^2 \left[\frac{1 - C_1^{\frac{d\theta_1}{dy}}}{1 + C_1 b_1} \right] - 200 C_1 A_1^2(o) \quad (11)$$

70 Referring next to FIGS. 2 and 3 the results of the computerized analysis is plotted showing the electron velocity and phase (both normalized) on a time-phase domain basis spaced over one period at various positions along the interaction path of the simulated tube model. Each dot designates the modu-

75

lated trajectory of one of the approximate 32 electron charge groups analyzed. The dashed lines 30 and 32 in FIGS. 2 and 3, respectively represent an equipotential surface along which the electrons are introduced at an average velocity normalized to a value of 1.0. The phase of the electron groups having a designated numerical value of between -0.5 and +0.5 is plotted along the horizontal coordinates and represents the normalized condition of the conventional $-\pi$ and $+\pi$ phase relationship with respect to the number of beam wavelengths along the interaction path. The computed velocity values are plotted along the vertical coordinate and cover a range of values from 0.3 to 1.4. FIG. 2 illustrates the electron group characteristics in the simulated traveling wave tube of prior art construction. FIG. 3 refers to the same characteristics of an illustrative embodiment of the invention having the profiled velocity shift phase-focusing means to increase efficiency.

The first reference frame in FIG. 2 depicts the initial beam modulation near the beginning of the interaction path where the level of such modulation is extremely low. The series of electron group trajectories traversing the periodic interval in the time-phase domain are collectively referred to by the numeral 34. A substantially sinusoidal path is noted with the decelerating field region oriented below line 30 while the accelerating or higher velocity electrons are bunched above the reference line. In accordance with well-known procedure the initial electron beam velocity is adjusted to be slightly greater than the velocity of the electromagnetic waves traveling in the same direction to optimize synchronous interaction. Consequently, the electron phase-focusing path assumes a deviation slightly to the right of the Ovalue crossover point in the reference frame.

Referring to the next position down the line we note the commencement of the formation of compact bunches in the decelerating field region, particularly at point 36 by reason of the modulating forces exerted on the electrons by the high-electric fields of the adjacent propagated waves. It will be noted that the prior art bunching to achieve a net interaction of electron kinetic energy with the guiding circuit waves commences at a normalized phase value of approximately 02.-0.3 or near the point of maximum decelerating forces in this field. The electrons have begun to slow down sufficiently to achieve the net transfer of energy and increase the amplitude of the axial electric field of the electromagnetic waves.

Still farther down the interaction path the electron groups will be observed to have even a tighter more definitive compact bunching pattern indicated by numeral 38. As the bunching becomes more compact the electromagnetic waveform illustrated by curve 40 continues to increase in amplitude by the appreciable fraction of kinetic energy converted into energy stored in the wave. The electromagnetic wave propagating on the guiding circuit has been shown only in this reference frame since the invention is dealing principally with the reorientation of the electron-bunching phenomena by preconditioning the beam for the region wherein the synchronous interaction bunching is established. The electromagnetic wave has been plotted with the horizontal line 42 indicating circuit modes along the interaction path and the arrow 44 indicates the amplitude of the electric field forces on the electron groups. The maximum bunching then, occurs in the approximate region shown by line 46 indicating the point of maximum decelerating force on the moving electron groups.

In the subsequent frame we observe saturation commencing when the total number of electrons in the accelerating and decelerating fields become substantially equal. The disarray of the previous tight bunches is noted in the area indicated by bracket 48. Further, electron groups 48, 50, 52 and 54 have drifted back into the accelerating region and are now of very little consequence for any further amplification.

In the final frame full saturation condition is achieved. Since the higher velocity electron groups rob energy from the propagated waves an undesirable condition is revealed in that the electron groups above the dashed line 30 indicated by the bracket 58 have relatively high velocities in the range of from

01. to 1.2. These electrons, therefore, have contributed relatively little to the net interaction process. Such residual "fast" electron groups at full saturation, then, indicate a possible area of efficiency enhancement by more complete utilization of the energy in electrons nearer the input region. The observation of electron groups having high-residual energy has continually plagued traveling wave interaction tubes since the high heat generated upon collection limits the power capabilities.

Bearing in mind then the observed inefficient phase focusing of electron groups in the simulated mathematical tube models of prior art devices, a device incorporating a suggested structure for enhancing efficiency by more favorable phase focusing will now be described. Attention is directed to FIG. 3 and in connection with this discussion the electromagnetic field waveform diagram shown in the middle reference frame has been numbered similarly to the one shown in FIG. 2.

Initial modulation shown by the collective path 60 is substantially similar in this region to the prior art devices. It is shortly thereafter, however, that the concept of the invention attempts to introduce a velocity shift at relatively low levels of beam energy extraction in order that a deliberate desynchronization will take place with the electron groups going faster than the propagated wave electric fields. At a subsequent position down the interaction path the synchronous relationship is restored. The primary objective of the invention resides in the shifting of the slower moving electron groups to a new position within the decelerating field region where they will be able to give up energy to the circuit waves over considerably longer periods of time. The shifting of the electron groups is desirably in a forward manner within the decelerating field toward the tube output end. This also permits a larger fraction of the electron groups to be eventually exposed to the decelerating field toward the tube output end. This also permits a larger fraction of the electron groups to be eventually exposed to the decelerating field before reaching tube saturation. The new velocity shift region is referred to in the specification as one of minimal decelerating forces and is located substantially between the -90° and 0° electromagnetic wave velocity value.

In the next frame the effects of the incorporation of structure for providing the phase-electron beam velocity shift will be noted. As a result of the desynchronization of interaction, the tight compact bunching previously noted in FIG. 2 at point 36 has now been moved slightly to the right to point 62 at phase value of between 0.4-0.5. Further on down the interaction path we observe a trajectory indicated generally by the numeral 64 with the slower moving electrons now being shifted to a point 66 within the decelerating field region. In relation to the electromagnetic waveform 40 the tight bunching of electron groups is now in the forward portion of the decelerating field as indicated by the line 68 in the region of between -90° and 0° wave phase velocity.

The level of beam modulation where the desired shift is provided to speed up the electron bunches or retard the propagated waves will generally be found in the region of from 20-10 db. down from the tube saturation or in the region of approximately 1-percent efficiency. The region will vary from device to device depending on operating frequency and bandwidth characteristics to provide an advance and/or retardation generally in a range of from 35°-90°. The manner of achieving the shift in phase focusing can be achieved in many ways depending on the wave guiding and beam parameters employed. Generally, such techniques as delay line severs, delay line tapers of the positive and/or negative variety, beam voltage potential jumps, separate phase shifters coupled to the wave-guiding circuit individually or combined can be employed. The analysis and judgment of the engineer is decisive to now provide a device having a programmed response determined mathematically without the need for costly empirical verification through construction of many prototype models. The intermediate velocity shift is provided either singularly along the interaction path or dually when a reestablishment of the

beam-wave synchronization is desired at a particular level of circuit phase velocity ratio (V_p/C). In the illustrative embodiment a shift of approximately 45° was introduced in the phase velocity propagating characteristics.

The subsequent reference frame illustrates an electron group path 70 having resynchronization established by a second velocity shift means, still well before the large signal region. The tight compact bunching at point 72 will be observed to be in the 0.3-0.5 phase value.

The beginning of the saturation reference frame has been purposely omitted to illustrate the resynchronization effect and would be substantially similar to the view in FIG. 2 which illustrates the beginning of the breaking up of the uniform electron bunch distribution and movement of electrons towards the accelerating field after giving up their energy. Turning next to the final view of complete saturation, however, the full import of the invention will be noted. The groups moving toward the accelerating field are indicated by the bracket 74 while those still in the decelerating field are indicated by the bracket 76. First, it should be observed that there are a larger number of electron groups approaching the accelerating field which indicates that they have delivered their kinetic energy to the circuit waves. In the analogous situation for prior art devices in FIG. 2 there are more electrons in the decelerating field awaiting a chance to exchange energy but never accomplishing this result because of saturation.

Secondly, whereas in the prior art situation we note a large number of "fast" electron groups above the electron velocity value of 1.0 within the bracket 58, now in the embodiment of the invention there is only one group of high-velocity electrons 78. This indicates more electrons have now been shifted to a more favorable phase-focusing position in the decelerating region for the net transfer of energy.

Further it should be noted that by the time the electron groups in the new embodiment reach tube saturation and drift back towards the accelerating field, the velocity values are considerably below the levels of the prior art embodiments. If the number of electron groups say at the 0.7 level of velocity and above at full saturation in FIG. 2 were counted, there would be nine such groups. These higher velocity electron groups indicate an inefficient net exchange of energy with the waves. In the exemplary embodiment of the invention in FIG. 3, however, only five such electron groups are noted above the 0.7 level and six electron groups are found in the 0.4 to 0.7 level. In addition, there are a total of seven groups of electrons which have given their energy to the waves and moved over to the accelerating region in the 0.4 to 0.7 level whereas in the prior art there were only three groups. The velocity shift to the forward portion of the decelerating region has actually been able to provide an additional amount of kinetic energy by a factor of from one-fourth to one-third to thereby increase power output by an efficiency factor of from 25-331/3 percent. With other improvements in tube structural characteristics such as depressed collector operation, overall efficiency improvement factors of 40-60 percent are now permissible.

Referring next to FIGS. 4 and 5 a helix-type delay line incorporating the teachings of the invention will be described. In FIG. 4 a helix-type wave-guiding structure 80 is illustrated incorporating the features of the invention for use in a forward wave-traveling wave interaction device similar to that shown in FIG. 1. In FIG. 5 a profile of the wave phase velocity ratio (V_p/C) where c is the speed of light is plotted over the length of the interaction path and indicated generally by line 82. The DC electron beam velocity which, as heretofore stated, is slightly greater than the propagated waves is plotted as dashed line 84. The input section 86 of the helix has a predetermined substantially uniform pitch, a term defined as the reciprocal of the number of turns per unit length. The characteristics of the wave-guiding structure in this region will follow conventional techniques for initial beam modulation and provides for a substantially constant phase velocity ratio adjacent the input end as shown by line portion 88 of the profile diagram.

At the point still at relatively low depths of beam modulation determined by the skilled artisan from analysis and the computerized study, a phase velocity shift in distances typically less than the fundamental circuit wavelength is introduced by means of a change in helix pitch or circuit-loading member 90 of the wave-propagating structure. The characteristic slope of the profile at this juncture can be represented by line portion 92. The phase velocity drops to a new level to substantially desynchronize the interaction process and allow the beam bunches to move or slide ahead faster in relation to the propagated waves. This shift creates an intermediate velocity region 94 in the profile diagram and since a tighter or closer spaced helix reduces phase velocity, an intermediate helix section 96 is provided to accomplish the desired result.

Resynchronization is established at a point 98 along helix 80 also predetermined by the computer analysis. Another velocity shift will, therefore, be introduced and a phase velocity 100 will be established in traversing the large signal region 106 before collection at the output end of the tube. Line 102 indicates the step to the new phase or output velocity on the profile diagram. The dual velocity shift concept, therefore, provides in essence what may be described as a notch over a predetermined interval in the tube phase velocity characteristics to achieve the desired reorientation of the electron bunches. The new wave phase velocity is maintained over a predetermined number of beam wavelengths over the tube overall length. The final or output section 104 of the helix may have a pitch dimension somewhere between the values in sections 86 and 96 to provide for overall efficient beam-wave interaction after the preconditioning of the electron beam modulation by the dual velocity shift.

Several methods of achieving the phase velocity changes have been heretofore noted. In any of the embodiments then, an electrical shift could be introduced in a wave-guiding structure having a uniform pitch throughout by a DC voltage jump which would increase the average beam velocity to a new level relative to the propagating wave velocity. This method, however, has the disadvantage of requiring an additional power supply and furthermore requires DC electrical isolation of the guiding structure. Such a DC electrical isolation requirement gives rise to the need for extremely careful circuit impedance matching. The illustrative structural techniques, therefore, shown in FIGS. 4 and 5 from the mechanical, as well as electrical standpoint, will generally be far simpler. Of course, imaginative combinations of the wave phase velocity shift, as well as DC beam velocity voltage jump, may be advantageously exploited in the practice of the invention.

FIG. 6 illustrates still another facet of the invention is to provide a very elaborate profile of phase velocity characteristics to tailor a beam in many different ways to enhance efficiency. The particular teaching together with its fruition as depicted in FIG. 7 relates to the so-called ring and bar delay line 200 which is relatively dispersive and, therefore, narrow band while the previously described helix-type guiding structure is relatively nondispersive and ideal for octave or extremely wide bandwidths. Actually, the ring and bar arises from a contrawound helix configuration. The disclosed guiding structure will be utilized for high-power traveling wave devices capable of providing many thousands or even tens of thousands of watts of high-frequency energy. In some instances many ring and bar sections may be mounted in tandem within a common envelope with up-to-date heat removal structures. The first portion or input section 108 of the overall profile diagram provides for a uniform wave phase velocity and to this end the bars numbered 1-43 inclusive of delay line 200 have a uniform spacing as indicated in the table FIG. 7. The structure referred to herein as bars comprises the solid portion 110 defined between the slotted sections 112 and indicated by the symbol T. Conventionally, such delay lines are machined from high-conductivity copper. It is a rather simple matter to mechanically alter the phase velocity configuration to the desired profile diagram by adjusting the overall length of each slotted sections 112 to thereby increase or decrease the dimensions of the bar section 10. The width of the slots

will be maintained uniform throughout the illustrative embodiment. For the purpose of the present description section A and the table shown in FIG. 7 covers the first 63 bar members and the section designated B covers the remainder of the delay line from bars 64 to 123 inclusive. Further, to assist in the interpretation of this embodiment of the invention the bar width dimensions in inches have been shown on the right hand vertical coordinate of FIG. 6. These values can easily be related to the description of the phase velocity changes in the ensuing description.

The portion of the section A from bar 44 until bar 64 represents the first velocity shift which it will be noted, is gradually tapered as indicated by the line 114. In many instances the gradual tapering may be preferable to a sharp drop in the velocity shift. Commencing from bar 44 designated by the numeral 116 we note a gradual progressive decreasing of the overall bar dimension from a value of approximately 1.350 inches to a value for bar number 63 denoted by numeral 118 of approximately 0.246 inches. Bars 60-82 inclusive define the overall shift portion 120 extending between sections A and B. At approximately the lowest point or in the vicinity of bars numbered 80 and 82 designated by the numerals 122 and 124, we observe the minimal bar width dimensions. At approximately bar 84 designated by the numeral 124 we perceive the gradual restoration of the synchronizing condition to the new level of phase velocity by gradually sloping line 126 and correspondingly progressively increasing bar width dimensions. In the remaining section of the ring and bar delay line we note another combination permissible within the teachings of the invention by the provisions of a gradually level section 128 and then a decreasing tapered section 130 approaching the output end. In this region we find the large signal region for the amplification of the propagated waves on the delay line structure. The profile diagram has been terminated at this point for the purpose of the description. In many applications it may be desirable to follow the foregoing velocity shift sections with another substantially uniform section at another phase velocity to provide for efficient synchronous interaction between the propagated waves and the shifted electron bunches. The remaining bar dimensions shown in FIG. 7 consist of bar members 132 and 134 indicates the members in the terminal portion of section B of the illustrated line. To provide a detailed enumeration of the values calculated by the computerized technique for 15 exemplary embodiment to handle extremely high-power microwave energy, attention is directed to the complete tables shown in FIG. 7.

Referring next to FIG. 8 the discussion now turns to the application of the subject invention to the enhancement of efficiency in octave bandwidth tubes where premature saturation due to harmonic frequency interference has plagued traveling wave interaction devices. It has been observed in the computerized analysis and study of such devices that a considerable amount of second harmonic frequency power actually exceeds that of the fundamental frequency power at the low end of the band. In devices having the observed second harmonic power exceedingly low efficiencies in the overall tube performance were noted. In the illustration the curves indicate the normalized force versus phase velocity for propagated waves near tube saturation to explain the interference process of the second harmonic component with the fundamental frequency components. All the curves are shown to represent one complete high-frequency RF energy cycle. Curve 136 is a plot of the fundamental space harmonic (F_1). Curve 138 is a plot of the second harmonic frequency components (F_2). Curve 140, then, represents the total force field (F_1+F_2) versus wave phase velocity. Attention is directed to the fact that the second harmonic power level P_2/P_1 is calculated to be 10 db. down from the fundamental and yet the relative force amplitude of the second harmonic stands at approximately 0.63 along the normalized force measurement coordinate. The beam bunch formation has been analyzed to have its charge density maximum occurring at approximately position A or

adjacent to the substantial midpoint of the fundamental wave-decelerating electric field. As saturation is approached deceleration of the beam bunches occurs and they drift toward position B under the influence of the large combined 5 high-frequency electric fields. This, it is believed, leads to premature tube saturation. Hence, it is this synchronous mechanism which has heretofore limited the efficiency attainment for, particularly, octave bandwidth traveling wave devices where second harmonic frequencies are involved.

10 In accordance with the teachings of the invention, then, utilizing structure heretofore described, as well as any other suitable structure known to the artisan, the interference of the second space harmonic field components on the amplification 15 of the fundamental harmonic frequencies may be substantially minimized by an appropriate shift at low levels of beam modulation to move the beam-bunches forward in phase to a position where the deceleration fields are minimal. Such a position is designated by the position C within the accelerating field of 20 the curve 136. Since the second harmonic frequency components are 180° out of phase at this point the fundamental frequency components still see the synchronous condition for amplification of the fundamental frequency waves now without the interference of the second harmonic field component. 25 As a result of the introduction of the velocity shift of, for example -90°, well before the saturation level, measurable improvements in efficiency in octave bandwidth tubes by factors of as high as 30 to 40 percent have been noted by reason of the reduction of premature saturation previously induced by 30 the second harmonic deceleration fields. Consequently, with this shift the second harmonic wave actually slips back in phase and favorably assists the beam-bunching process induced by the fundamental wave.

In FIG. 9 three distinct possible combinations will be 35 reviewed. Curve 142 indicates a traveling wave device having a 15-percent phase velocity shift. The dotted line 144 depicts the phase of beam charge density for a device without the velocity shift mechanism. Finally, dashed line 146 indicates the situation for the propagation of a fundamental signal alone 40 without any velocity shift. Clearly, the phase of the beam charge density shows a decided improvement in the region between 9-15 beam wavelengths for more efficient synchronous interaction.

The additional kinetic energy available for power conversion will provide for an increase in efficiency as noted in the 45 next illustration, FIG. 10. In this view the efficiency values are plotted along the vertical coordinate while the same distance dimensions in terms of beam wavelengths are indicated along the horizontal coordinate. The solid line 148 indicates a traveling wave device covering the second harmonic, as well as fundamental frequencies, with an approximate 15-percent phase velocity shift in the wave-guiding structure. The dotted line 150 shows the expected efficiency with the harmonic 50 frequencies and no velocity shift which clearly results in efficiency degradation. Clearly then, it is evident that for a uniform wave-guiding circuit, particularly in the instance of octave bandwidth tubes, the harmonic interference process is substantial leading to premature saturation and very low efficiencies.

60 In FIG. 11 the illustration provides a comparison of harmonic power variation as a function of distance along the tube length for comparison of the results of embodiments incorporating the structure of the invention. Curve 152 indicates the simulated power gain for the fundamental frequency only and no velocity shift. The dashed line 154 appended to curve 65 152 indicates the 15 power gain with a velocity shift of approximately 15 percent. Similarly, solid curve 156 is a simulation of the power gain of the second space harmonic frequency and the dashed line 158 indicates the drop and then recovery in gain of the second harmonic power in a tube with the velocity shift. It is obvious from a study of this illustration that the drop in gain in the second harmonic frequency signal is substantially inconsequential in terms of the increase in the power gain of the fundamental frequency signal. In the large 70 75

signal region the reduced level of second harmonic power prolongs saturation with an accompanying increase in the fundamental signal power in tubes with the velocity shift which produces improved phase focusing. The prior art efficiency degradation as a result of the excessive second harmonic power content in octave bandwidth traveling wave devices has, therefore, been measurably improved through the introduction of the velocity shift technique of the invention. At tube saturation the reduction in the second harmonic power content indicates the contribution to the fundamental power gain.

A final alternative embodiment of the velocity shift technique of the invention may be noted in FIG. 12 for incorporation in a device having a substantially uniform wave-guiding circuit 160 with input and output ends 162 and 164, respectively. A suitable phase shifter indicated generically by box 166 is coupled to the line in the region closely adjacent to the input end or the region of low level beam modulation to introduce the desired shift of the phase velocity characteristics as hereinbefore outlined. In this manner the phase of the waves being propagated may be delayed by any value up to 90° to provide for the advancement of the electron bunches to the minimal region of the decelerating electric fields of the propagating waves.

The realization that the tailoring of the beam-wave velocity characteristics in the initial stages of beam modulation may considerably affect or enhance efficiency should be an impetus in the further utilization of both narrow, as well as octave bandwidth traveling wave interaction devices, for communications, as well as radar system applications. Both the second harmonic frequency interference process, as well as narrow band fundamental frequency signal amplification and/or generation, have been discussed in the foregoing description. There is a wide range of combinations which may be evolved in the practice of the invention to provide tube output characteristics heretofore believed unattainable utilizing prior art utilizing prior art structures. In view, therefore, of the many variations modifications and alterations which will be apparent to those skilled in the art relating to the disclosed invention, the foregoing description is intended as one for illustrative purposes only. All such variations, therefore, are intended to be encompassed by the broad interpretation of the scope and breadth of the invention as set forth and defined in the appended claims.

What is claimed is:

1. A traveling wave electron interaction device comprising: a wave-guiding circuit means for propagating electromagnetic wave energy;

means for generating and directing a beam of electrons along a path adjacent to said wave-guiding circuit means to interact in an energy exchanging relationship with the propagated waves;

and means for varying the electron beam-wave interaction relationship by reducing the circuit phase velocity ratio (Vp/C) where C is the velocity of light at substantially low levels of beam modulation sufficient to provide for a shift in electron bunching within the decelerating electric fields of said propagated waves and increase the net overall energy transfer between said electrons and said waves.

2. A traveling wave electron interaction device comprising: a wave-guiding circuit means for propagating electromagnetic wave energy;

means for generating and directing a beam of electrons along a path adjacent to said wave-guiding circuit means to interact in an energy exchanging relationship with the propagated waves;

and means for introducing a discontinuity in the phase velocity characteristics of said guiding circuit means at an intermediate region along said interaction path to reduce said phase velocity;

said region being oriented at substantially low levels of

beam modulation sufficient to provide for optimal bunching of electrons within the decelerating electric fields of said propagated waves to increase the net overall energy transfer between said electrons and said waves.

3. A traveling wave electron interaction device comprising: wave-guiding circuit means having an input and output terminal for propagating electromagnetic wave energy; means for generating and directing a beam of electrons along a path adjacent to said wave-guiding circuit means to interact in an energy exchanging relationship with the propagated waves;

and means for varying the electron beam velocity characteristics by reducing the circuit phase velocity ratio (Vp/C) where C is the velocity of light at substantially low levels of beam modulation sufficient to provide for advancement in phase of the modulating electron bunches relative to the decelerating electric fields of said propagated waves in a direction toward the output terminal and increase the net overall energy transfer.

4. A traveling wave electron interaction device comprising: a wave-guiding circuit for propagating electromagnetic waves;

means for regenerating and directing a beam of electrons along a path adjacent to said circuit to interact in an energy exchanging relationship with said waves;

and means for varying the electron beam-wave interaction relationship by reducing the circuit phase velocity ratio (Vp/C) where C is the velocity of light at substantially low levels of beam modulation sufficient to provide for an advance in phase of electron bunching relative to the waves on said circuit of between 45°-90° within the decelerating electric fields of said waves with a resultant increase in net overall energy transfer.

5. A traveling wave electron interaction device comprising: A wave-guiding circuit for propagating electromagnetic waves;

means for generating and directing a beam of electrons along a path adjacent to said circuit to interact in an energy-exchanging relationship with said waves;

and means for varying the electron beam-wave interaction characteristics by reducing the circuit phase velocity (Vp/C) where C is the velocity of light sufficient to provide for an advance in phase of the modulating electron bunches relative to the decelerating electric fields of said waves at a point 10to 20 db. below the saturation level of the device.

6. A traveling wave electron interaction device comprising: a wave-guiding circuit having an input and output terminal for propagating electromagnetic waves;

means for generating and directing a beam of electrons along a path adjacent to said circuit to interact in an energy-exchanging relationship with said waves;

and means for varying the electron beam-wave interaction characteristics by reducing the circuit phase velocity (Vp/C) where C is the velocity of light to provide for an advance in phase of the modulating electron bunches relative to the decelerating electric fields of said waves in a region along the length of the device where the value of the electromagnetic circuit power level is in the order of 1 percent of power at the output terminal.

7. A traveling wave electron interaction device comprising: a wave-guiding circuit structure for propagating electromagnetic waves;

means for generating and directing a beam of electrons along path adjacent to said structure to interact in an energy-exchanging relationship with said waves;

and means for varying the electron beam-wave interaction characteristics by reducing the circuit phase velocity ratio (Vp/C) where C is the velocity of light in the region of substantially low levels of beam modulation in conformance with a mathematically programmed profile pattern to introduce a desynchronizing characteristic in the relationship of the phase of said electron and propagated wave velocities and shift the

electron beam bunches within the decelerating electric fields of said waves to a more favorable energy exchanging position with a resultant increase in net overall energy transfer.

8. A traveling wave electron interaction device comprising: a periodic slow wave circuit structure for propagating electromagnetic waves;

means for generating and directing a beam of electrons along a path adjacent to said structure to interact in an energy exchanging relationship with said waves;

means for reducing the ratio of electron beam-wave velocity

5

characteristics (Vp/C) where C is the velocity of light to yield a substantially nonsynchronous relationship over a portion of said interaction path in the region of substantially low levels of beam modulation and shift the velocity of electron beam bunches within the decelerating electric fields of said waves;

and means for establishing a synchronous interaction relationship with a predetermined ratio of electron beam to wave velocity disposed sequentially to said velocity shift region.
